US0D1098059S

(12) **United States Design Patent** (10) **Patent No.:** **US D1,098,059 S**
(45) **Date of Patent:** **** Oct. 14, 2025**

(54) **CIRCUIT BOARD**

(71) Applicant: **The Noco Company**, Glenwillow, OH (US)

(72) Inventors: **James P. McBride**, Phoenix, AZ (US); **Matthew Michael Bosway**, Gilbert, AZ (US)

(73) Assignee: **The Noco Company**, Glenwillow, OH (US)

(**) Term: **15 Years**

(21) Appl. No.: **29/918,905**

(22) Filed: **Nov. 30, 2023**

Related U.S. Application Data

(63) Continuation of application No. 29/767,470, filed on Jan. 22, 2021, now Pat. No. Des. 1,010,591.

(57) **CLAIM**

The ornamental design for a circuit board, as shown and described.

DESCRIPTION

FIG. 1 is a perspective view of a new design for a circuit board;

FIG. 2 is a front elevational view thereof;

FIG. 3 is a right side elevational view thereof;

FIG. 4 is a left side elevational view thereof;

FIG. 5 is a top plan view thereof; and

FIG. 6 is a bottom plan view thereof;

FIG. 7 is another perspective view of a new design for a circuit board;

FIG. 8 is a front elevational view thereof;

FIG. 9 is a right side elevational view thereof;

FIG. 10 is a left side elevational view thereof;

FIG. 11 is a top plan view thereof;

FIG. 12 is a bottom plan view thereof; and,

FIG. 13 is a rear elevational view thereof.

The broken lines shown in the drawings illustrate unclaimed portions and form no part of the claimed design.

1 Claim, 13 Drawing Sheets
